UNITED STATES PATENT OFFICE

JOSEPH A. McCARTHY, OF RICHMOND HILL, NEW YORK

DESIGN FOR A FLUE CAP

Application filed January 25, 1930. Serial No. 34,290. Term of patent 7 years.

To all whom it may concern:

Be it known that I, JOSEPH A. McCARTHY, a citizen of the United States of America, residing at Richmond Hill, in the county of Queens and State of New York, have invented a new, original, and ornamental Design for Flue Cap, of which the following is a specification, reference being had to the accompanying drawing, forming part thereof.

Figure 1 is a side elevational view of a flue cap showing my new design;

Figure 2 is a front elevational view of the same; and

Figure 3 is a rear elevational view of the same.

I claim:—

The ornamental design for a flue cap, as shown.

JOSEPH A. McCARTHY.
